COMBINED BENCH AND DISPLAY UNIT

Richard Owen Abbott, 140 Newbury St.,
Boston, Mass. 02116

Filed Dec. 14, 1966, Ser. No. 5,038

Term of patent 14 years

(Cl. D80—9)

FIG 1

FIG 2

FIG 3

FIG 4

FIG 5

FIG 6

FIG. 1 is a perspective view of a combined bench and display unit showing the new design;

FIG. 2 is a reduced top plan view thereof;

FIG. 3 is a reduced side elevation view thereof;

FIG. 4 is a perspective view of a modified form of the combined bench and display unit shown in FIG. 1;

FIG. 5 is a top plan view of FIG. 4; and

FIG. 6 is a side elevation view of FIG. 4.

What is claimed is:

The ornamental design for combined bench and display unit, as shown and described.
